The ornamental design for a tab as shown and described.

DESCRIPTION

FIG. 1 is a top perspective view of a tab of the design; FIG. 2 is an alternative top perspective view of a tab of the design;

FIG. 3 is a top view of the tab of FIG. 1;

FIG. 4 is a top view of the tab of FIG. 2;

FIG. 5 is a bottom view of the tab of FIG. 1;

FIG. 6 is a bottom view of the tab of FIG. 2;

FIG. 7 is a front view of the tab of FIGS. 1 and 2;

FIG. 8 is a back view of the tab of FIGS. 1 and 2;

FIG. 9 is a left view of the tab of FIGS. 1 and 2; and,

FIG. 10 is a right view of the tab of FIGS. 1 and 2.

In the drawings, the broken lines show portions of a tab and a container that form no part of the claim. The tab container is shown with a symbolic break in its length. The appearance of any portion of the article between the dash-dot-dash break line forms no part of the claimed design.
